United States Patent Office

Des. 222,448
Patented Oct. 26, 1971

222,448

STEERING WHEEL

Thomas L. Faul, Skaneateles, N.Y. and John Smith, Willowdale, Ontario, and Hugo Magi, Etobicoke, Ontario, Canada, assignors to Aqua-Marine Mfg. Limited, Toronto, Ontario, Canada

Filed Sept. 22, 1970, Ser. No. 25,147

Term of patent 14 years

Int. Cl. D12—16

U.S. Cl. D14—30

FIG. 1

FIG. 2

FIG. 3

FIG. 4

In the drawings:

FIG. 1 is a perspective view from the top and side of a steering wheel showing our design;

FIG. 2 is a perspective view from the bottom and side of the steering wheel of FIG. 1;

FIG. 3 is a top plan of the steering wheel of FIG. 1; and

FIG. 4 is a side elevation of the steering wheel of FIG. 1.

We claim:

The ornamental design for a steering wheel, as shown.
